FIG. 2

FIG. 3

1

**MEMBRANE STRUCTURE FOR
INTEGRATED PRODUCTION OF WATER
BALL**

**CROSS-REFERENCE TO RELATED
APPLICATIONS**

This application claims priority to Chinese patent application No. 202311421694.1 filed Oct. 30, 2023. The contents of this application are incorporated herein by reference in their entirety.

TECHNICAL FIELD

The present disclosure relates to the technical field of 15 toys, and in particular, to a membrane structure for integrated production of a water ball.

BACKGROUND

A water ball can be used as a toy and other utensils. The water ball is formed by injecting water into a water pocket. In case of a requirement for a large-scale production of water balls, it is inefficient to inject water into the water pockets one by one, which affects the improvement of the production 25 efficiency.

SUMMARY

The present disclosure aims to at least solve one of the 30 technical problems in the existing technology. Therefore, the present disclosure provides a membrane structure for integrated production of a water ball.

The technical scheme taught by the present disclosure to solve the technical problems is to provide a membrane structure for integrated production of a water ball, including an integrated membrane, where the integrated membrane includes a membrane body portion and a pocket body portion, and a pocket body tear line is arranged between the membrane body portion and the pocket body portion; and the membrane body portion is provided with a water injection channel, and a one-way water inlet is arranged between the water injection channel and the pocket body portion.

According to the membrane structure for integrated production of a water ball provided by the present disclosure, at 35 least the following technical effects are realized: with a design in which a membrane is connected to a plurality of pocket body portions, it is only necessary to connect the integrated membrane to a water source during production, so as to inject water into the pocket body portions through the water injection channel; and after the water injection is completed, the pocket body portion can be torn out to obtain a water ball with water injected; and the one-way water inlet ensures that the water will not flow back out.

In some preferred embodiments of the present disclosure, the integrated membrane is formed at least by laminating two single membranes, and a cavity between the two single membranes is used as a cavity of the pocket body portion and the water injection channel.

In some preferred embodiments of the present disclosure, the water injection channel includes a main water injection channel and a branch water injection channel, and the branch water injection channel is in communication with the one-way water inlet.

In some preferred embodiments of the present disclosure, the main water injection channel is provided with a main water injection tear opening.

2

In some preferred embodiments of the present disclosure, the one-way water inlet includes a membrane flat pipe, and the membrane flat pipe includes a flat pipe water inlet and a flat pipe stretching portion.

5 In some preferred embodiments of the present disclosure, the one-way water inlet includes a peripheral limiting and pressing edge.

In some preferred embodiments of the present disclosure, the pocket body portion is peripherally provided with a peripheral reinforcing and pressing edge.

10 In some preferred embodiments of the present disclosure, both ends of the membrane body portion are provided with a clamping portion.

In some preferred embodiments of the present disclosure, a clamping portion tear line is arranged between the clamping portion and the membrane.

15 In some preferred embodiments of the present disclosure, the membrane body portion is provided with an outer tear line at an outer side of the membrane body portion, and the outer tear line is connected to the pocket body tear line.

20 The beneficial effects of the present disclosure are as follows:

1. the newly designed membrane is of a sheet-like shape before water injection, and therefore is convenient to be stored;
2. during the water injection, several pocket body portions on the membrane can be injected with water at the same time by a single water injection, which improves the efficiency of production;
3. after the water injection, the pocket body portion is torn out to be used as a water ball, such that the operation is simple and convenient; and
4. the new design is not only suitable for water injection of a water ball, but also suitable for injecting other fluids, for example, the new design is also suitable for gas injection of a balloon.

35 Additional aspects and advantages of the present disclosure will be set forth in part in the following description, some of which will be apparent from the following description, or will be learned by practice of the present disclosure.

BRIEF DESCRIPTION OF DRAWINGS

Additional aspects and advantages of the present disclosure will become apparent and readily appreciated from the following description of the embodiments with reference to the accompanying drawings. In the drawings,

40 FIG. 1 is a schematic diagram of a structure according to the present disclosure;

FIG. 2 is an enlarged view of a part of a pocket body portion according to the present disclosure; and

FIG. 3 is a schematic diagram of a pocket body portion 45 after water injection according to the present disclosure.

DETAILED DESCRIPTION

60 Embodiments of the present disclosure will be described in detail below, and examples of the embodiments are shown

in the accompanying drawings, where the same or similar reference numerals indicate the same or similar elements or elements having the same or similar functions throughout. The embodiments described below with reference to the accompanying drawings are illustrative only for the purpose of explaining the present disclosure, and are not to be construed as limiting the present disclosure.

In the description of the present disclosure, it should be understood that the directions or positional relationships indicated by terms such as "upper", "lower", "front", "rear", "left", "right" and the like are those shown based on the accompanying drawings, and are merely intended to facilitate and simplify the description of the present disclosure rather than indicating or implying that the indicated apparatus or element must have a specific direction and must be configured and operated according to the specific direction. Therefore, these directions or positional relationships should not be construed as limiting the present disclosure.

In the description of the present disclosure, "multiple" means two or more, and "greater than", "less than", "more than" and the like are understood as excluding the original number. In the description of the present disclosure, unless otherwise explicitly defined, terms such as "arrange", "mount", "connect" and the like should be understood in a broad sense, and those skilled in the art can reasonably determine the specific meanings of the above terms in the present disclosure in conjunction with the specific contents of the technical schemes.

FIG. 1 is a schematic diagram of a structure according to an embodiment of the present disclosure. Referring to FIG. 1, an embodiment of the present disclosure provides a membrane structure for integrated production of a water ball, which is used to inject water into a plurality of water ball products at a time to improve the production efficiency of water balls.

Further, the membrane structure for integrated production of a water ball includes an integrated membrane, where the integrated membrane includes a membrane body portion 100 and a pocket body portion 200, and a pocket body tear line 110 is arranged between the membrane body portion 100 and the pocket body portion 200. That is, the whole membrane body portion 100 is a sheet-like structure before water injection, and the pocket body portion 200 can be torn out of the membrane body portion 100 through the pocket body tear line 110 to form a separate pocket body portion 200.

Further, a water injection channel 300 is arranged on the membrane body portion 100, and a one-way water inlet 400 is arranged between the water injection channel 300 and the pocket body portion 200. That is, the pocket body portion 200 is injected with water through the water injection channel 300, and the one-way water inlet 400 ensures that the water in the pocket body portion 200 will not flow back out after the water injection.

Referring to FIG. 2, during actual production, it is only necessary to take out the integrated membrane and connect the water injection channel 300 to a water source, such that the water can be injected into the pocket body portion 200 on the membrane body portion 100 through the water injection channel 300. The pocket body portion 200 with water injected is then expanded from a sheet-like shape into a ball-like shape. Referring to FIG. 3, after the water injection is completed, the expanded pocket body portion 200 can be torn out of the membrane body portion 100 through the pocket body tear line 110 to obtain a water ball with the water injection completed. The one-way water inlet 400 ensures that water in the pocket body portion 200 will

not flow back out during and after the water injection process and even after the pocket body portion 200 is torn out.

In some embodiments, the pocket body portion 200 may also be used as a balloon when being injected with gas.

In some embodiments, referring to FIG. 1, the integrated membrane is formed at least by laminating two single membranes, and a cavity between the two single membranes is used as a cavity of the pocket body portion 200 and the water injection channel 300.

In some embodiments, the water injection channel 300 includes a main water injection channel 320 and a branch water injection channel 330, and the branch water injection channel 330 is in communication with the one-way water inlet 400, that is, a branch water injection channel 330 corresponds to a pocket body portion 200. In this way, when water is injected, it is only necessary to connect the main water injection channel 320 to one water source.

In some embodiments, the main water injection channel 320 is provided with a main water injection tear opening 310, and the main water injection channel 320 can be connected to the water source for receiving water after the main water injection tear opening 310 is torn.

In some embodiments, referring to FIG. 2, the one-way water inlet 400 includes a membrane flat pipe 410, and the membrane flat pipe 410 includes a flat pipe water inlet 411 and a flat pipe stretching portion 412. When water is injected through the one-way water inlet 400, the membrane flat pipe 410 is enough to ensure a water flow to be smoothly injected into the pocket body portion 200. After the water injection is completed, the flat pipe stretching portion 412 of the membrane flat pipe 410 will be bent under the action of water pressure and be in a state of closely adjacent to an inner wall of the pocket body portion 200, and in this state, the water in the pocket body portion 200 cannot leak through the membrane flat pipe 410.

In some embodiments, the one-way water inlet 400 can be a one-way valve structure of other balloons or water balls in the existing technology.

In some embodiments, the one-way water inlet 400 includes a peripheral limiting and pressing edge 420 for improving the structural strength of the pocket body portion 200 at the position of the one-way water inlet 400, and especially for preventing the one-way water inlet 400 from being damaged when the pocket body portion 200 is torn out.

In some embodiments, the pocket body portion 200 is peripherally provided with a peripheral reinforcing and pressing edge 210 for improving the overall structural strength of the pocket body portion 200, and especially for preventing a peripheral line position from being damaged when the pocket body portion 200 is torn out.

In some embodiments, both ends of the membrane body portion 100 are provided with a clamping portion 500 to facilitate the clamping of the membrane body portion 100 by a machine.

In this embodiment, optionally, the clamping portion 500 is embossed with an anti-slip pattern.

In some embodiments, a clamping portion tear line 120 is arranged between the clamping portion 500 and the membrane body portion 100 to facilitate the tearing of the clamping portion 500.

In some embodiments, the membrane body portion 100 is provided with an outer tear line 130 at an outer side of the membrane body portion, and the outer tear line 130 is connected to the pocket body tear line 110, such that an outer portion of the membrane body portion 100 can be torn out

along the outer tear line 130, and the pocket body portion 200 can be exposed and easily torn out.

In the description of the specification, the description with reference to the terms "some embodiments" or "it may be contemplated" or the like means the specific features, structures, materials or characteristics described in combination with the embodiment or example are included in at least one embodiment or example of the present disclosure. In this specification, the schematic expression of the above terms does not necessarily refer to the same embodiments or examples. Furthermore, the specific features, structures, materials, or characteristics described can be combined in any suitable manner in any one or more embodiments or examples.

Although the embodiments of the present disclosure have been shown and described, it may be understood by those of ordinary skill in the art that various changes, modifications, substitutions, and alterations may be made to these embodiments without departing from the principle and purpose of the present disclosure, and the scope of the present disclosure is defined in the claims and equivalents thereof.

What is claimed is:

1. A membrane structure for integrated production of a water ball, comprising an integrated membrane, wherein the integrated membrane comprises a membrane body portion and a pocket body portion, and a pocket body tear line is arranged between the membrane body portion and the pocket body portion; and

wherein the membrane body portion is provided with a water injection channel, and a one-way water inlet is arranged between the water injection channel and the pocket body portion.

2. The membrane structure for integrated production of a water ball according to claim 1, wherein the membrane body portion is formed at least by laminating two single membranes, and a cavity between the two single membranes is used as a cavity of the pocket body portion and the water injection channel.

3. The membrane structure for integrated production of a water ball according to claim 1, wherein the water injection channel comprises a main water injection channel and a branch water injection channel, and the branch water injection channel is in communication with the one-way water inlet.

4. The membrane structure for integrated production of a water ball according to claim 3, wherein the main water injection channel is provided with a main water injection tear opening.

5. The membrane structure for integrated production of a water ball according to claim 1, wherein the one-way water inlet comprises a membrane flat pipe, and the membrane flat pipe comprises a flat pipe water inlet and a flat pipe stretching portion.

6. The membrane structure for integrated production of a water ball according to claim 1, wherein the one-way water inlet comprises a peripheral limiting and pressing edge.

7. The membrane structure for integrated production of a water ball according to claim 1, wherein the pocket body portion is peripherally provided with a peripheral reinforcing and pressing edge.

8. The membrane structure for integrated production of a water ball according to claim 1, wherein both ends of the membrane body portion are provided with a clamping portion.

9. The membrane structure for integrated production of a water ball according to claim 8, wherein a clamping portion tear line is arranged between the clamping portion and the membrane body portion.

10. The membrane structure for integrated production of a water ball according to claim 1, wherein the membrane body portion is provided with an outer tear line at an outer side of the membrane body portion, and the outer tear line is connected to the pocket body tear line.
